TREATMENT OF FILAMENTS, FOILS, AND
SIMILAR ARTICLES

Thomas Barnard Frearson and Thomas Jackson,
Spondon, near Derby, England, assignors to
Celanese Corporation of America, a corpora-
tion of Delaware

Application January 8, 1947, Serial No. 720,856
In Great Britain January 21, 1946

5 Claims. (Cl. 28—59.5)

1

This invention is concerned with improvements in or relating to stretching and other treatments of filaments, yarns, foils and similar products carried out during their travel through a fluid under pressure, and to apparatus for carrying out such treatments.

It is well-known that the tenacity of filaments, yarns, foils and similar articles made of organic derivatives of cellulose and other polymeric compounds may be improved very considerably by stretching them in the presence of steam or other stretch-assisting agent. For example, U. S. application S. No. 4,510, filed February 1, 1935, now abandoned, describes the stretching of continuous filaments and threads made of cellulose acetate in the presence of saturated or wet steam under pressure, and U. S. Patent No. 2,142,909 describes an improved apparatus in which the materials pass first through an end pressure chamber containing a positively driven feed device for the materials and then into a stretching chamber. Both of these specifications indicate that the means for introducing the steam into the stretching chamber is preferably such as to direct the steam on to the filaments or threads immediately upon their entry into the chamber.

The methods and apparatus described in these and other patents give very valuable results as regards the tenacity of the filaments and other articles produced and it is possible, as described in the above specifications, to stretch yarns to more than fifty times their original length if desired and to double or treble their original tenacity. We have, however, now discovered that it is not essential that the steam should be directed on to the articles immediately upon their entry into the stretching chamber but that, on the contrary, it is advantageous to protect them from the direct impact of the steam, particularly when yarns of high denier, such as are employed in the production of tyre cords and the like, are to be stretched. Such yarns usually consist of a number of ends and may have a total denier, for example, of 5,000, 10,000, 15,000 or even 20,000.

The protection of the yarns from the direct impact of the steam, which may be moving with a high velocity, may be carried out merely by interposing a shield between the yarns and the steam inlet orifices, but preferably the yarns are caused to pass through an open-ended box or "shroud" at that portion of their path through the stretching chamber where they would otherwise be subjected to the impact of the steam, and the steam inlet orifices are so arranged that the steam impinges on the outer side of the shroud

5 and not on the yarns. The width and depth of the shroud employed should be such that the yarns can pass easily through it without any risk of their rubbing against it. It may, for example, be six to twelve inches wide, depending on the number of ends of yarn dealt with by the machine, and one to two inches deep. Its length, in the direction of travel of the yarns, should be sufficient completely to shield the yarns from the 10 jets of steam entering the stretching vessel. Usually a length of three to six inches is sufficient.

When, as is preferred, the steam is introduced near the orifices through which the yarns enter the stretching chamber, the shroud may consist 15 of an open-ended box fixed to the wall containing the yarn inlets and surrounding these inlets, or fixed to a separate removable plate provided with an opening for the passage of the yarns and adapted to be positioned in contact with or adjacent to the wall containing the yarn inlets.

20 The steam inlets may consist of a large number of very small orifices, but it has been found preferable to use fairly large inlet orifices having a diameter, for example, of $\frac{3}{16}$ " or $\frac{1}{8}$ ", or even one or more large orifices having a size, for example, of 1" x $\frac{1}{4}$ ". An advantage of the use 25 of the larger orifices is that they are less likely to become blocked by particles of solid matter present in the steam, with the result that maintenance costs arising from the necessity for cleaning the orifices are reduced.

A stretching machine embodying the invention is illustrated in the accompanying drawing. The machine comprises yarn feeding means and 30 take-up means (not shown), and between them an end pressure box 1 and a stretching chamber 2 having as a common end wall with the end pressure box 1 a plate 3. The end pressure box 1 is provided with orifices at one end for the entry 35 of the yarns (not shown) and at the other end with orifices 4 in the plate 3 for their passage into the stretching chamber 2; the stretching chamber is provided with orifices 5 in its output end for the passage of the yarns to the take-up means. The cross-section of the orifices in the end pressure box and in the plate 3 is substantially 40 equal to that of the unstretched yarn, while that of the orifices 5 is substantially equal to that of the yarn after it has been stretched.

45 In the stretching chamber 2 a plate 6 is clamped to the plate 3 with suitable packing to effect a perfect seal between the two plates. The plate 6 is provided with a slot 7 of such shape and size as to allow the free passage of yarn from each 50 of the orifices 4, and around this slot is fixed a

shroud 8 extending perpendicularly to the plate 6 for 3 to 6 inches into the stretching chamber 2. The stretching chamber 2 also comprises a steam jet plate 9 consisting of steam inlets 10, channels 11 above and below the shroud 8, and orifices 12 in the walls of the said channels whereby steam is caused to enter the stretching chamber and impinge on the outer surfaces of the shroud 8.

As has already been stated, the invention has been found to be particularly valuable in the stretching of yarns of high denier, such as are used for the production of tyre cords and beltings. Not only are the stretched yarns more uniform and the stability of stretching better, but also the invention makes it possible to stretch bundles of a higher total denier than in the absence of a shroud. A number of yarns, e. g. in warp formation, can be stretched simultaneously without loss of uniformity. For example, in the production of stretched yarns for tyre cords it has been found that by using a shroud nine inches wide, one inch deep and three inches long fixed round the orifices through which the yarns enter the stretching chamber it is possible to stretch a set of 20-25 bundles of yarn, each bundle having a denier four times as great as could be stretched satisfactorily in the absence of the shroud. Moreover, the use of a shroud also makes it possible to increase the load on the machine, expressed in terms of denier per unit width of feed roller, even though the number of ends per unit width is reduced as a result of the increase in the denier per end. In consequence the theoretical output per unit time of a machine has been increased by nearly 40% and this, coupled with improved efficiency due to quicker starting and longer runs also resulting from the use of the shroud, has resulted in an increase in production per machine of over 70%.

Though the invention is of the greatest value for the stretching of yarns of high denier, it is applicable in general to stretching and other treatments of yarns, especially cellulose acetate yarns, filaments, foils and similar articles carried out during their travel from one point to another through a vessel containing a fluid treatment agent under pressure. For example, cellulose acetate yarns of 250 to 500 denier may be stretched to ten times their original length in wet steam in the apparatus described in the present application, and used for textile purposes, if desired after conversion into regenerated cellulose yarns by complete saponification. Cellulose acetate yarns of fine denier, e. g. 40-50, may also be successfully stretched to give very uniform products.

In general the conditions for stretching articles made of cellulose acetate or other organic derivative of cellulose are similar to those described in the prior specification referred to above, though it has been found that when the shroud is in use it is preferable to employ a slightly higher steam pressure, e. g. higher by $\frac{1}{2}$ pound per square inch, than in the absence of the shroud. The best results, especially when stretching yarns of high denier or when stretching to a high degree, e. g. to six, ten or more times the original length of the yarns, are obtained with an apparatus having an end pressure chamber as described in U. S. Patent No. 2,142,909 in which case the end chamber preferably contains water at a pressure somewhat lower than that of the steam, for instance about 2 to 5 pounds per square inch below the steam pressure.

As already stated the invention is also applicable to stretching and other treatments of fila-

ments, yarns, foils and similar articles made of thermoplastic polymeric compounds other than those made of organic derivatives of cellulose. Examples of such compounds are polyvinyl acetate, polyvinyl chloride, polyvinyl acetate-vinyl chloride and polyvinylidene chloride.

The invention has been described with particular reference to the types of stretching apparatus illustrated in U. S. application S. No. 4,510, filed February 1, 1935, and U. S. Patent No. 2,142,909 but it is to be understood that the principle is applicable generally to apparatus used for stretching and other treatments in which fluid media, particularly gaseous media, are introduced under pressure. For instance, in apparatus provided with an injector device such as is described in U. S. application S. No. 472,460, filed January 15, 1943, now Patent No. 2,450,045, of T. Jackson and F. B. Hill, the orifice 12 through which the yarn enters the stretching chamber may be prolonged so as to protect the yarn from the direct impact of the steam or other fluid introduced through the annular orifice 5.

Having described our invention, what we desire to secure by Letters Patent is:

1. In apparatus for stretching yarns in warp formation in wet steam under pressure comprising a pressure stretching chamber having inlet and outlet orifices for the yarns, each orifice being substantially of the same size and shape as the cross section of the yarn to pass through it, and having close to, but separate from, the inlet orifices for the yarns, inlets for the steam directed towards the path of the yarns near to the inlet orifices for the yarns so that the steam would normally impinge directly on the yarns, the improvement which consists in the provision of a shroud surrounding the path of the yarns in the vicinity of the yarn inlet orifices and sufficiently long to prevent the steam from impinging directly on the yarns, said shroud being interposed between the steam inlets and the path of the yarns whereby the steam impinges on said shroud, and said shroud being freely open to the pressure treatment chamber whereby the steam is present on all sides of said shroud and is in a relatively quiescent state when it initially contacts the yarns.

2. In apparatus for stretching yarns in warp formation in wet steam under pressure comprising a pressure stretching chamber having inlet and outlet orifices for the yarns, each orifice being substantially of the same size and shape as the cross section of the yarn to pass through it, and having close to, but separate from, the inlet orifices for the yarns, inlets for the steam directed towards the path of the yarns near to the inlet orifices for the yarns so that the steam would normally impinge directly on the yarns, the improvement which consists in the provision of a removable plate in contact with the wall of the chamber containing the inlet orifices for the yarns, the said plate being provided with an opening in front of the said inlet orifices by means of which the yarns pass through the plate, and with a shroud mounted round the said opening and extending into the chamber, the length of the shroud being sufficient to prevent the steam from impinging directly on the yarns, said shroud being interposed between the steam inlets and the path of the yarns whereby the steam impinges on said shroud, and said shroud being freely open to the pressure treatment chamber whereby the steam is present on all sides of said shroud and is

in a relatively quiescent state when it initially contacts the yarns.

3. In apparatus for stretching yarns in warp formation in wet steam under pressure comprising a pressure end chamber having inlet and outlet orifices for the yarns and contiguous therewith a pressure stretching chamber having inlet and outlet orifices for the yarns, each of all the said orifices being substantially of the same size and shape as the cross section of the yarn to pass through it, and having close to, but separate from, the inlet orifices for the yarns into the stretching chamber, inlets for the steam directed towards the path of the yarns so that the steam would normally impinge directly on the yarns, the improvement which consists in the provision in the stretching chamber of a shroud surrounding the path of the yarns in the vicinity of the yarn inlet orifices and sufficiently long to prevent the steam from impinging directly on the yarns, said shroud being interposed between the steam inlets and the path of the yarns whereby the steam impinges on said shroud, and said shroud being freely open to the pressure treatment chamber whereby the steam is present on all sides of said shroud and is in a relatively quiescent state when it initially contacts the yarns.

4. In apparatus for stretching yarns in warp formation in wet steam under pressure comprising a pressure end chamber having inlet and outlet orifices for the yarns and contiguous therewith a pressure stretching chamber having inlet and outlet orifices for the yarns, each of all the said orifices being substantially of the same size and shape as the cross section of the yarn to pass through it, and having close to, but separate from, the inlet orifices for the yarns into the stretching chamber, inlets for the steam directed towards the path of the yarns so that the steam would normally impinge directly on the yarns, the improvement which consists in the provision of a shroud 3 to 6 inches long surrounding the path of the yarns in the vicinity of the yarn inlet orifices to prevent the steam from impinging directly on yarns, said shroud being interposed between the steam inlets and the path of the yarns whereby the steam impinges on said shroud, and said shroud being freely open to the pressure treatment chamber whereby the steam is present on all sides of said shroud and is in a relatively quiescent state when it initially contacts the yarns.

5. In apparatus for stretching yarns in warp formation in wet steam under pressure compris-

ing a pressure end chamber having inlet and outlet orifices for the yarns and contiguous therewith a pressure stretching chamber having inlet and outlet orifices for the yarns, each of all the said orifices being substantially of the same size and shape as the cross section of the yarn to pass through it, and having close to, but separate from, the inlet orifices for the yarns into the stretching chamber, inlets for the steam directed towards the path of the yarns so that the steam would normally impinge directly on the yarns, the improvement which consists in the provision of a removable plate in contact with the wall of the stretching chamber containing the inlet orifices for the yarns, the said plate being provided with an opening in front of the said inlet orifices by means of which the yarns pass through the plate, and with a shroud mounted round the said opening and extending into the chamber for a length of 3 to 6 inches to prevent the steam from impinging directly on yarns, said shroud being interposed between the steam inlets and the path of the yarns whereby the steam impinges on said shroud, and said shroud being freely open to the pressure treatment chamber whereby the steam is present on all sides of said shroud and is in a relatively quiescent state when it initially contacts the yarns.
